The ornamental design for a two-sided zipper pull/keychain ornament for engaging a decorative button, as shown and described.

DESCRIPTION

FIG. 1 is a perspective view of our ornament;

FIG. 2 is a top plan view;

FIG. 3 is a bottom plan view;

FIG. 4 is a left side view, the right side view being a mirror image;

FIG. 5 is a front plan view; and,

FIG. 6 is a back plan view.

It being understood that the broken lines are for illustrative purposes only and form no part of the claimed design.
